(57) **CLAIM**

The ornamental design for a ceiling fan assembly, as shown and described.

DESCRIPTION

FIG. 1 is a front elevational view of a ceiling fan assembly showing my new design;

FIG. 2 is a rear elevational view showing the design for the ceiling fan assembly of FIG. 1;

FIG. 3 is a left side elevational view showing the design for the ceiling fan assembly of FIG. 1;

FIG. 4 is a right side elevational view showing the design for the ceiling fan assembly of FIG. 1;

FIG. 5 is a top plan view showing the design for the ceiling fan assembly of FIG. 1;

FIG. 6 is a bottom plan view showing the design for the ceiling fan assembly of FIG. 1; and,

FIG. 7 is a perspective view showing the design for the ceiling fan assembly of FIG. 1.

In FIGS. 1-7, the broken lines showing of various items including the ceiling, the cover plate secured to the ceiling, the electrical wire extending from the cover plate, the electrical wires extending from the electrical box to the fan units, the screw eyes and associated support linkages extending from the ceiling, the upper grille portion of each fan unit, the support structure for the fan units that is interposed between the upper horizontal support member and the support linkages, the lattice work that is interposed between the upper horizontal support member and the lower horizontal support member, and the various cover members that are respectively interposed between the various lattice work sections is for illustrative purposes only and forms no part of the claimed design.
